UNITED STATES PATENT OFFICE

2,422,390

SHOE PRESS

Pincus Brauner, Haverhill, Mass.

Application June 12, 1946, Serial No. 676,215

8 Claims. (Cl. 12—33)

1

This invention relates to improvements in shoe presses of the general type which have an adjustable post between which and an inflatable pad a suitably supported shoe upper structure and a sole element may be effectively combined by pressure applied as a result of inflation of the pad. More particularly the invention provides improvements in the post and its mounting means in such a press whereby the work more readily and quickly may be inserted in and removed from the press and may be effectively positioned and conditioned in the press for a more thorough and efficient application thereto of the combining pressure.

It is among the objects of the invention to provide a shoe press including an inflatable pad, and a work engaging post having means thereon for carrying the work and which is movable to swing the work carrying means between a loading position and a pressing position, and is movable axially in the pressing position to thrust the work on the work carrier into unyielding engagement with the pad prior to inflation of the pad.

Another object is to provide a shoe press including an inflatable pad, and a work engaging post having means thereon for carrying the work and which constantly is biased to swing the work carrying means laterally to a loading position whenever the work on the work carrying means is clear of the inflatable pad.

Still another object is to provide a shoe press including an inflatable pad, and a work-holding post constantly biased laterally to a loading position and constantly biased axially in general direction away from the pad, there being means for thrusting the post axially in opposition to said axial bias prior to inflation of the pad.

Yet another object is to provide a shoe press including an inflatable pad, and a work-holding post constantly biased axially in general direction away from the pad, there being means for inflating the pad and means for thrusting the post axially in opposition to its said bias in response to actuation of said inflating means and prior to actual inflation of the pad.

It is, moreover, my purpose and object generally to improve the structure and operational effectiveness of shoe presses.

In the accompanying drawings:

Fig. 1 is a front elevation of a two-jack shoe press embodying features of my invention;

Fig. 2 is a side elevation of the upper portion of the left hand jack of Fig. 1, on a larger scale, and with the work holder retracted and clear of the pad, as just prior to swinging thereof to its loading position;

Fig. 3 is a cross-sectional view on line 3—3 of

Fig. 2;

Fig. 4 is a cross-sectional view on line 4—4 of Fig. 1, on a larger scale;

2

Fig. 5 is a cross-sectional view on line 5—5 of Fig. 2, on a larger scale;

Fig. 6 is an elevation of the lower end of one of the work-holding posts with a modified form 5 of last-holder thereon; and

Fig. 7 is a cross-sectional view, partly diagrammatic, illustrating a pressure-operated post-actuating means.

Referring to the drawings, a two-jack shoe press is shown in Fig. 1, mounted upon the table 10 of a stand 12. As each jack or press is the same, only one is herein described in detail, although the operating mechanism for the two jacks preferably is such that one press is conditioned for unloading and re-loading while the other is active on a shoe engaged therein.

Each jack has a base 14 secured as by screws 16 to the table 10, and any suitable inflatable pad 18 is fixed in position on each base 14 with its flexible top wall 19 adapted to rise and fall with inflation and deflation of the pad. Any usual or suitable means may be employed for admitting fluid to the interior of the pad, and for exhausting fluid from the pad following each pressing operation. In the two-jack press illustrated, the control is in response to depression of one or the other of the pedals 20, 22 of a double treadle 24 which is connected to the outer end of an operating rock shaft 26. Depression of one pedal 20 causes inflation of one pad while the other continues deflated, and depression of the other pedal produces the same result in reverse.

The base 14 of each jack has an integral vertical part 28 rising to a suitable height above the pad 18, rearward thereof, with its upper end portion enlarged and provided with the generally rectangular horizontal hole 30 therethrough constituting a socket for reception of the correspondingly rectangular shank 32 of a post-supporting mechanism indicated generally at 34. The shank 32 may be secured in its socket by a set screw 36 or the like.

Referring more particularly to Figs. 2 and 4, the shank 32 has a cylindrical head 38 formed at its inner end within which a sleeve 40 is rotatably mounted, the head 38 having a slot 42 in its wall, and the sleeve 40 having a pin 44 projecting into the slot and limiting the rotation of the sleeve in the head by engagement with the opposite ends of slot 42. A coil spring 46 within head 38 has one end connected to the head and the other end connected to the sleeve, with the spring constantly biasing the sleeve in direction to bring pin 44 against one end wall of slot 42.

Sleeve 40 extends beyond the inner end of head 38, and the projecting part of the sleeve carries at its end a generally cylindrical guide portion 48 whose axis is at right angles to the axis of sleeve 40. A post 50 extends loosely and slidably 55 through the guide portion 48 and has its lower

region threaded as at 52 for screwing into the interiorly threaded collar 54 which is arranged below the guide portion 48. A hand wheel 55 is mounted on the extreme upper end of the post for manual adjustment of the post in collar 54.

The extreme lower end of post 50 is rotatably anchored in the carried member 56 which includes the holder part 57 deeply grooved at its under side as at 58 for reception of a work-holding member which may be a shaped element for fitting within a shoe upper, such as the element 60 of Figs. 1, 2 and 4, or may be a bar 122 as shown in Fig. 6 having a spring biased pin 124 for engaging in the usual heel socket of a last. In either case, the work-holding member readily may be mounted or replaced in holder 57 by means of a headed stud 66 whose shank is insertible in and removable from registering holes in the holder 57 or in whichever work-holding member is mounted therein. Adjustable set screws 68 in the holder 57, on each side of stud 66, may be adjusted to make the work-holding member substantially rigid in holder 57 with selected degrees of inclination, if desired, relative to holder 57.

According to the invention, the post 50, besides being manually adjustable by rotation of hand wheel 55, is bodily movable in axial directions by moving the sleeve 54 axially relative to the cylindrical guide 48. For this purpose, a thrust bar 70 extends generally parallel with the axis of the main sleeve 40, spaced a little above the cylindrical head 38. The inner end of the thrust bar has a pair of ears 72 depending at opposite sides of the projecting part of the sleeve 40, adjacent the inner end of head 38. The opposite side walls of the sleeve 40 are slotted as at 74, and a piston 76 within sleeve 40 has oppositely projecting trunnions 78 thereon, each projecting through a slot 74 and through one of the ears 72 of thrust bar 70. A relatively strong coil spring 80 within sleeve 40 constantly biases the piston outwardly or away from post 50 with the trunnions limiting the outward travel of the piston by engagement with the outer end walls of the slots 74.

The outer ends of a pair of toggle links 82, one at each side of sleeve 40, are pivotally connected to the trunnions 78, as at 84. The inner end of each link 82 is pivotally connected at 86 to the outer end of one of the two toggle links 88, 90 whose outer ends are pivotally connected respectively to the cylindrical guide 48, as at 92, and to the post-supporting sleeve 54, as at 94. The length of the slots 74 in sleeve 40 determines the amount of movement of sleeve 54 and post 50 which can be effected by actuation of thrust bar 70, and the inner limit of the slots preferably is such that the toggle links 88, 90 will be slightly beyond an on-center position when the thrust bar 70 is in its innermost position.

The outer end of the thrust bar 70 is swivelly connected at 96 to the upper end of a lever 98 which may be pivoted on any convenient fixed support which, as herein shown, is a rod or shaft 100 mounted within the rear hollow portion of base 14 with one end projecting out of the base and having lever 98 fixed thereon as at 99.

If desired, each lever 98 may be provided with means (not shown) for manual actuation of the lever. However, I prefer that the actuation of levers 98, and of the toggle mechanisms heretofore described, shall be automatic in response to actuation of the usual mechanism for inflating and deflating the pads 18. To this end, each pivot shaft 100 has fixed thereon interiorly of a base 14 a relatively short arm 102 which is equipped

with a roller 104. Preferably, the roller 104 is mounted in a yoke member 106 having a threaded shank 108 extending loosely through the arm 102, with lock nuts 110 on the shank at each side of the arm by means of which the roller may be adjusted toward or from the lever arm. The rear wall of base 14 is cut away to provide room for swinging of arm 102, and to facilitate adjustment of the roller.

A shaft 112 is mounted in the side walls of each base 14 and extends across its hollow, with a cam 114 fixed on the shaft interiorly of the base 14. The roller 104 rides on the periphery of the cam which has the inclined flat cam surface 114' and the concentric cam surface 114'', with the latter surface constituting the high part of the cam. The lever operating mechanism for both jacks may be the same excepting that the cam 114 for one jack will be reversed with respect to the other cam, so that when one roller 104 is riding on the concentric surface 114'' of one cam, the other roller 104 will be riding on the inclined flat surface 114' of the other cam.

The cam 114 is free to rotate on shaft 112 by means of arm 116 fixed to the cam and connected at its free end to an actuating rod or bar 118 which extends through the table 10 and interiorly of stand 12, with its lower end connected to the rock bar 120 on the treadle rock shaft 26. There is a separate shaft 112, cam 114, arm 116 and rod or bar 118 for each jack. Hence, when pedal 20 is depressed to inflate pad 18 of the left hand jack, for example, in Fig. 1, the cams 114 will be rocked in opposite directions. The concentric portion of the cam 114 for the left hand jack will be moved into engagement with its roller 104, and the roller on the cam 114 for the right hand jack will ride from the concentric portion to the inclined flat portion of the cam. In consequence, lever 98 of one jack is actuated to straighten its toggle and to depress its post 50, and lever 98 of the other jack is permitted to swing in toggle-breaking direction under the urge of its spring 80, thereby to elevate its post 50 to a position where its spring 46 can swing the work holder to a loading position beside the jack or press.

When pedal 22 is depressed, the operation as above described is reversed.

It should be understood that the initial depression of a pedal 20 or 22 actuates one cam to straighten the toggle of one jack, and simultaneously actuates the other cam in direction to permit breaking of the toggle of the other jack, before the control valve moves enough to initiate inflation of the pad of the first mentioned jack and deflation of the pad of the second mentioned jack.

Fig. 6 shows a modified form of work holder in which a bar 122 is substituted for the member 60 of the previously described apparatus. Bar 122 may be mounted in the holder 56 by means of the pin 66 and may be adjusted to a proper setting by the set screws 68. The bar has a spring-pressed pin 124 depending and normally biased by its spring to the canted full line position of Fig. 6. The pin is adapted for insertion in the usual socket 126 of a last 128, with the pin forced, against its bias, to a vertical position when inserted in the socket 126, so that the pin bias tends to swing the last to bring its forepart against a toe abutment 130 adjustably depending from bar 122. Friction between the pin and the socket walls holds the last on the pin, with the forepart pressed against the toe abutment. Actuation of

the work is the same as described in connection with Figs. 1-5.

If desired, the actuation of the toggle of each jack may be accomplished by fluid pressure from the same source of fluid pressure which inflates the pads 18. In Fig. 7, the sleeve 40' which guides a post 50 has the same piston 76 therein as that shown in Fig. 4. An exteriorly threaded disk 132 is screwed into the hollow of sleeve 40' to constitute an end wall of a cylinder chamber 134. Fluid under pressure is introduced into chamber 134 as through conduit 136 which has a flexible portion 136' to permit rotation of sleeve 40' by the spring 46' the same as described in connection with the apparatus of Figs. 1-5. When pressure fluid enters chamber 134 it propels piston 76 in direction to straighten the toggle, and when the cylinder is opened to atmosphere, the spring 80 breaks the toggle, as previously described.

Fluid under pressure, from any suitable source, may be controlled by a valve 138 (Fig. 7) which serves both to control the inflating and deflating of the pads 18 and to control the admission of pressure fluid to the cylinder chambers 134, and the exhausting of those cylinders. As shown, the valve comprises an outer casing 139 through whose wall extends the inlet conduit 140, the exhaust conduits 142, a conduit 144 connected to one pad 18, and a conduit 146 connected to the other pad 18. Also a conduit 148 through the outer casing connects through one conduit 136 with one of the cylinder chambers 134, and a conduit 150 through the outer casing connects through the other conduit 136 with the other cylinder chamber 134. A branch conduit 152 connects the two exhaust conduits 142 with a single exhaust conduit 143. A rotatable valve member 156 has the two grooves 158, 160 in a face thereof, shown in Fig. 7, with groove 158 connecting conduit 144 to exhaust and with groove 160 connecting conduit 150 to exhaust. Hence, with the valve element 156 positioned as shown in Fig. 7, the pad 18 with which conduit 144 connects will be deflated and the cylinder chamber 134 with which conduit 150 connects will be open to atmosphere. Conduit 146 leading to the other pad 18 is exposed to pressure from conduit 140 and this pad 18 will be inflated. Also conduit 148 leading to the other cylinder chamber 134 is open to pressure from conduit 140 so that fluid is open into this latter chamber and, in Fig. 7 is about to force piston 76 to toggle straightening position.

Rotation of member 156 clockwise in Fig. 7 first opens conduit 150 to pressure fluid and then opens conduit 144 to fluid pressure, so that the toggle for the jack whose cylinder is thus opened to pressure will be straightened before the pad 18 connected to conduit 144 is inflated. At the same time both conduit 146 and conduit 140 are connected to exhaust.

The control valve represented by dotted lines in Fig. 1 is generally similar to the valve of Fig. 7 excepting that the rotatable element 156' may be a disk with two similar arcuate grooves 158', 160', for controlling only the four conduits represented in the Fig. 1 valve.

I claim as my invention:

1. In a shoe press having a generally horizontally disposed inflatable pad, work supporting mechanism for coaction with the pad, comprising a support fixed relative to the pad, a member mounted on the support and extending in general parallelism with the pad at a fixed location above the pad, a post disposed with its axis gen-

erally transverse of the direction of extent of said member and having a work holder at one end and means for manually rotating the post at its other end, means on said member slidably engaging said post intermediate of its ends, means threadedly engaging said post between said slidably engaging means and one end of the post, means including a toggle for quick-traverse movement of said threadedly engaging means relative to said slidably engaging means thereby to move said post and work holder to and from coacting relation to the inflatable pad, said toggle maintaining said threadedly engaging means against rotation whereby the work holder may be manually adjusted relative to the pad by manual rotation of the post through the medium of said manually rotating means at an end of the post.

2. In a shoe press having a generally horizontally disposed inflatable pad, work supporting mechanism for coaction with the pad, comprising a support fixed relative to the pad, a member mounted on the support and rotatable on a generally horizontal axis at a fixed distance above the pad, means limiting the permissive rotation of said member in both directions, means constantly biasing said member toward one of its said limits of rotation, a post carried by said member and disposed with its axis generally transverse of the axis of said member, means for manual rotative adjustment of the post in axial directions relative to said member, work holding means at one end of the post, the said limits of rotation of said member providing for lateral swinging of said work holder about the axis of said member between a loading position laterally outward from the pad and a position directly over the pad, and means including a toggle for quick-traverse movement of the work holder relative to said member and pad in directions axially of said post.

3. In a shoe press having a generally horizontally disposed inflatable pad, work supporting mechanism for coaction with the pad, comprising a support fixed relative to the pad, a cylindrical member mounted on the support and rotatable about a generally horizontal axis at a fixed distance above the pad, means biasing said member in one direction above its axis, means limiting the rotation of said member in both directions, a post carried by said member at a location over said pad, said post being disposed with its axis transverse of the axis of said member whereby rotation of said member swings one end of the post between a position in which the axis of the post is perpendicular to the pad and a loading position laterally outward from the pad, said biasing means acting in direction tending to maintain said end of the post in said loading position, and means including a toggle for quick-traverse movement of the post in directions axially of the post.

4. In a shoe press having a generally horizontally disposed inflatable pad, working supporting mechanism for coaction with the pad, comprising a work holding post, a member supporting the post in which the post is rotatively adjustable in directions axially of the post, means supporting said member and post for swinging thereof on a horizontal axis thereby to swing the work holding portion of the post between a pressing position over the pad and a loading position laterally outward from the pad, means biasing said supporting means in one direction about its horizontal axis thereby tending to maintain said work holding portion of the post in said loading position, and a toggle connection

between said member and said supporting means for quick-traverse movement of said member relative to said supporting means thereby to move the post in directions axially of the post.

5. In a shoe press having a generally horizontally disposed inflatable pad, work supporting mechanism for coaction with the pad, comprising a post having work holding means at one end, means supporting the post for movement in axial directions between retracted and extended positions and for lateral swinging of its work holding end from a pressing position above the pad, in which latter position the axis of the post is generally perpendicular to the pad, and a loading position laterally outward from the pad, means biasing the post axially to said retracted position, means biasing said work holding end of the post to said loading position, said work holding end being manually movable against its bias to said pressing position, and means for moving the post axially from said retracted position to said extended position when said work holding end thereof is in pressing position thereby to thrust said work holding end toward the pad.

6. In a shoe press having a generally horizontally disposed inflatable pad, work supporting mechanism for coaction with the pad, comprising a support above the pad and fixed relative thereto, a member mounted on said support and rotatable on a horizontal axis, a post having work holding means at one end, means mounting said post on said member with its axis transverse of the axis of said member, means biasing said member in one direction about its horizontal axis whereby said biasing means tends to swing the work holding end of the post from a pressing position over said pad to a loading position laterally outward from the pad, means biasing said post mounting means in one direction of axial extent of the post, and means for quick-traverse movement of said post mounting means in opposition to its said bias thereby to thrust the work holding end of the post in the opposite direction of axial extent of the post.

7. In a shoe press having a generally horizontally disposed inflatable pad, work supporting mechanism for coaction with the pad, comprising a support at a fixed location above the

pad, a cylinder mounted on the support and rotatable on a horizontal axis, a guide fixed at one end of the cylinder with its axis transverse of the cylinder axis, a post extending slidably and rotatably through said guide and having work holding means at one end, a collar threaded on said post below said guide, means for manual rotative adjustment of the post in axial directions in said collar, means for moving the collar relative to the guide in axial direction generally toward the pad, means biasing the collar in axial direction generally away from the pad, and means biasing said cylinder in one direction about its axis thereby to swing the work carrying end 15 of the post to a loading position laterally beside the pad when said collar biasing means moves said end clear of the pad following a pressing operation.

8. In a shoe press having a generally horizontally disposed inflatable pad, work supporting mechanism for coaction with the pad, comprising a support at a fixed location above the pad, a cylinder mounted on the support and rotatable on a horizontal axis, a guide fixed at one 20 end of the cylinder with its axis transverse of the cylinder axis, a post extending slidably and rotatably through said guide and having work holding means at one end, a collar threaded on said post below said guide, resilient means enabling said support and said cylinder and biasing the cylinder in one direction about its axis, means including a toggle for moving said collar axially relative to said guide, resilient means within the cylinder and connected to said toggle 25 biasing said sleeve in its axial direction generally away from the pad, and means for rotative manual axial adjustment of the post in said collar.
